US00D756762S

(12) **United States Design Patent**
Hohmann, Jr.

(10) **Patent No.:** **US D756,762 S**
(b4) **Date of Patent:** **** May 24, 2016**

(54) **HIGH-STRENGTH PARTITION TOP ANCHOR**(71) Applicant: **Columbia Insurance Company**,
Omaha, NE (US)(72) Inventor: **Ronald P. Hohmann, Jr.**, Hauppauge,
NY (US)(73) Assignee: **Columbia Insurance Company**,
Omaha, NE (US)(***) Term: **14 Years**(21) Appl. No.: **29/519,399**(22) Filed: **Mar. 4, 2015****Related U.S. Application Data**

(63) Continuation of application No. 13/797,102, filed on Mar. 12, 2013, now Pat. No. 8,978,326.

(51) **LOC (10) Cl.** ..... **08-08**(52) **U.S. Cl.** **D8/382**

Primary Examiner — Ian Simmons*Assistant Examiner* — Leisha Price(74) *Attorney, Agent, or Firm* — Senniger Powers LLP(57) **CLAIM**

The ornamental design for a high-strength partition top anchor, as shown and described.

DESCRIPTION

FIG. 1 is a perspective view of a high-strength partition top anchor according to the present invention;

FIG. 2 is a front view of the high-strength partition top anchor of FIG. 1, the rear view being identical thereto;

FIG. 3 is a left side view of the high-strength partition top anchor, the right side view being identical thereto;

FIG. 4 is a top view of the high-strength partition top anchor; and,

FIG. 5 is a bottom view thereof.
